UNITED STATES PATENT OFFICE.

WILLIAM E. FORD, OF CARTHAGE, MISSOURI.

ORE-CONCENTRATOR.

1,060,333.

Specification of Letters Patent. Patented Apr. 29, 1913.

Application filed April 12, 1908. Serial No. 489,431.

To all whom it may concern:

Be it known that I, WILLIAM E. FORD, a citizen of the United States, residing at Carthage, in the county of Jasper, State of Missouri, have invented certain new and useful Improvements in Ore-Concentrators, of which the following is a specification.

This invention relates to ore concentrating apparatus of the type in which the reduced ore is treated on a table to which peculiar vibratory motions are imparted and across which is caused to flow a film or thin sheet of water, the ore thereon being first stratified and then concentrated.

It has for its object to improve the concentrating table in the manner illustrated in the accompanying drawings and hereinafter described.

Figure 1 of the drawings is a plan view of the concentrating table showing the riffle arrangement. Fig. 2 is a longitudinal sectional view of the table. Fig. 3 is a transverse sectional view, parts being broken away, illustrating the braces for maintaining the surface of the table in a plane. Figs. 4, 5, 6 and 7 are transverse sectional views taken respectively on the lines IV, V, VI and VII of Fig. 1. In the drawings 4 designates the concentrating table which is supported in any suitable manner, and to which is imparted reciprocatory motions, as is common in apparatus of the type to which my invention belongs, for the purpose of effecting the separation of the valuable from the worthless parts of the mass of fine material treated on the surface of the table. It is preferably rectangular in shape and provided with a series of riffles 50 which I will presently describe in detail. In order to maintain the working surface of the table as nearly in a perfect plane as possible and to correct any tendency for it to warp out of shape, I employ bracing devices, illustrated in Fig. 3, which are located along the longitudinal edges of the table. Referring particularly to this view, 24, 24 indicate inclined brace rods supported at their outer ends in the floor plates 28 which are secured to the underside of the bed of the concentrating table close to the outer edges thereof.

At their inner ends these braces are supported in brackets 25 carried by the longitudinal sills or track beams 8 of the table. Nuts 26 engage with the screw-threaded parts of the brace rods and, lying on the opposite sides of the brackets 25, constitute means by which the rods are adjusted and maintained under proper stress to keep the surface of the table in approximately a perfect plane.

Concentrating tables of the class to which my invention belongs customarily have imparted to them reciprocatory motions of a peculiar nature—the forward movements thereof being more rapid than those in a rearward direction—in order to effect the advancement of the ore longitudinally along the table, and at the same time, in conjunction with the wash of the water flowing across the table, to cause the separation of the valuable from the worthless ingredients of the ore. In my Patent 830,425 dated September 4, 1906, there is shown a driving mechanism for reciprocating the table such as may be employed. It is however unnecessary to illustrate said driving mechanism in order to understand the invention herein presented.

In the treatment of ore by means of apparatus such as described two operations upon the material being treated take place as has already been alluded to, namely, stratification and concentration. While both of these operations are taking place to a certain degree throughout the entire active surface of the concentrating table, the stratification is principally effected near the head or feeding-on end of the machine, while the concentration takes place principally toward the delivery end. To promote these operations it is customary to provide the table with standing ribs or riffles which are usually arranged parallel with each other and with the lines of reciprocation of the table. They usually have vertical edges and are highest toward the feeding-on end of the table and thence gradually taper toward the delivery end. In my aforesaid patent there is illustrated and described a form of riffle which I have discovered to be

highly efficient. It consists of a central rib portion having vertical side edges and a base portion from which the rib rises, having upper surfaces that slope away from the main rib. The rib part of the riffle, that is the part having vertical standing edges, inclines downward from the head toward the tail end of the table, while the base portion of the riffle—the part having inclined upper surfaces,—extends beyond the said rib and finally merges into the flat surface of the table near the tail or discharge end thereof. It is now well understood that the riffles with vertical edges cause the wash water flowing transversely across the table to form eddies adjacent to the standing edges, and that stratification of the material being treated is facilitated by reason of this breaking up of the flow of the water. The continuation of the lower or base portions of the riffles beyond the central or ribs parts thereof, as illustrated and described in my aforesaid patent, instead of having the riffles terminate in the plane of the table where the ribs leave off, has been found to facilitate the concentration of the values found in the ores, particularly those of finer grade. I have discovered that better results are attained if the shape of the base portion of the riffle is changed beyond the termination of the central rib part thereof; that is to say, if the surfaces of the base portions have a different slope beyond the standing ribs, that is toward the discharge end of the machine, from what they do toward the head end of the machine or between the ribs. This portion of my invention is illustrated in Figs. 4 to 7 inclusive, where 50 designates the central standing rib portions of the riffles having vertical side walls, and 51 the base portions having sloping upper surfaces. The shape of the base portions of the riffles at different parts of the table is indicated by the transverse sectional views 5 to 7.

As illustrated in Fig. 1 the riffles 50 change their direction longitudinally. In the arrangement illustrated the riffles bend or change their direction twice; once along the line *x* and again along the line *y*. The location or disposition of the line or lines along which the riffles change their direction is not very material, the important fact being the bending or changing direction of the riffles between their ends in order that the paths along which the concentrates lying between adjacent riffles are conducted shall be bent or broken, as thereby two objects are secured. First, there is a change in the angle of the flow of the water over the concentrates in their line of travel or movement lengthwise of the table which I have found tends to more rapidly separate the sand and other waste material from the valuable par-

ticles than where the channels formed by the riffles are straight throughout. In the second place, the arrangement of riffles referred to tends to the better stratification of the particles of value. The reciprocatory motions imparted to the table give to the heavy particles of ore movement in a longitudinal direction, which movement is interrupted or impeded at the places where the direction of the riffles is changed, with the result as I have found, that there is a better and more perfect stratification and consequent final concentration. It is desirable that the bends or changes in the direction of the riffles should be such as to change the direction of the channels between the riffles toward the upper edge of the table, at least this should be true of the bends nearest the delivery end of the table if the direction of the riffles is changed more than once. It is well known that the fines tend to hug or move close to the riffles. These fines being heavier than the waste material upon the table tend to settle down close to the bed, and, by reason of their small size, they shift down between the values of larger size. Being exceedingly small particles they are easily acted upon by the wash water, and, owing to their size, are less readily moved toward the discharge end of the table than are the particles of larger size. It is therefore desirable to give the riffles such direction as will assist in keeping the fines of value on the upper edge or side of the table along with the larger values, and this I have found can be accomplished by changing the direction of the riffles and inclining them one or more times in a direction toward the upper edge of the table so that the angle at which they diverge is decreased toward the discharge end of the table.

What I claim is:

1. An ore concentrating table having longitudinal sills and provided along its edges with strips or plates, in combination with screw threaded brace rods connected at their outer ends with the said strips or plates and at their inner ends supported by the said sills, and nuts for putting the brace rods under stress to maintain the surface of the table in a plane.

2. An ore concentrating table supported so as to be reciprocated and provided with riffles arranged to permit stratification of the ore being treated at the head end of the table and concentration at the delivery end, the riffles having ribbed portions with vertical side walls tapering from the head toward the tail of the machine, the said ribs rising from base portions of the riffles having sloping upper surfaces, the said base portions extending beyond the ribbed portions of the riffles toward the delivery end of the table, and the inclination of the said

sloping upper surfaces differing at different parts of the riffles longitudinally, substantially as and for the purpose set forth.

3. An ore concentrating table adapted to be reciprocated, provided with longitudinal riffles, the direction of the riffles being twice slightly changed in the course of their length by angular bends, the last change be-

ing toward the upper or water feed side of the table and the riffles being straight except at the bends.
